UNITED STATES PATENT OFFICE.

ARTHUR O. HIGINBOTHAM, OF DENVER, COLORADO, ASSIGNOR OF ONE-HALF TO WILLIAM A. WEIGELE, OF DENVER, COLORADO.

APPARATUS FOR SUPPLYING OXYGEN TO COMBUSTION CHAMBERS.

Original application filed August 15, 1924, Serial No. 732,323. Divided and this application filed July 11, 1925. Serial No. 43,044.

This invention relates to an improved mechanism for the controlled supply of oxygen to the fire bed of a boiler or other furnace, after its replenishment with fresh fuel,

5 to effect a substantially complete combustion of the gases emanated from the burning fuel and thereby prevent the formation of smoke and escape of partially oxidized and unoxidized combustible gases and the consequent waste of heat units.

It is an object of the invention to provide a simple, practical and efficient mechanism which is automatically actuated after the furnace is supplied with fuel, to admit oxygen to the fire at a predetermined rate and during a predetermined space of time.

A further object of the invention is to include in the above stated mechanism, readily effected adjustments whereby the oxygen supply may be varied in accordance with different requirements and another aim of the invention resides in carrying the above objects into effect by means of a cam-operated damper, and a time mechanism for the 25 operation of the damper.

In the accompanying drawings, the invention has been illustrated in operative relation to the hinged fire-door of a furnace but it is to be understood that a different moving part of a furnace, as, for example, the reciprocating piston ram of a mechanical push-stoker, may be employed for the same purpose without material changes in the construction or arrangement of the elements of 30 the invention.

In the accompanying drawings in which similar characters of reference designate corresponding parts throughout the several views.

40 Figure 1 represents a front view of a portion of a furnace wall and a door closing the fire-opening thereof, with the elements and parts comprised in the present invention in operative relation thereto, the casing enclosing the time-element of the mechanism having been shown in vertical section;

45 Figure 2, an enlarged vertical section along the line 2—2, Figure 1;

Figure 3, a similar section taken along the 50 line 3—3, Figure 1;

Figure 4, an enlarged section in the plane indicated by the line 4—4 in Figure 1;

Figure 5, a section similar to that of Figure 4, showing the members of the cam-

movement in the position they occupy when 55 the dampers of the furnace have been opened to the full extent of their predetermined movement;

Figure 6, a fragmentary enlarged section along the line 6—6, Figure 1;

Figure 7, a sectional detail of the adjustable anti-friction wheel which transmits the movement of the cam-element of the invention to the dampers which control the admission of oxygen to the fire box of 65 the furnace; and

Figure 8, an enlarged face-view of the cam-element of the invention.

The present application is divisional of my application for Patent No. 732,323, filed 70 on the 15th day of August 1924.

Referring to the drawings, 5 designates the wall of a boiler or furnace, having a fire-opening and a door 7 hinged at 8, which normally closes the same.

75 The door has an opening defined by a forwardly projecting rectangular flange 9, through which, in practice, air is admitted to the combustion chamber of the furnace, and the air-opening is normally closed by two lapping dampers 10 hung for pivotal movement about horizontal axes, by means of shafts 12 supported in openings of the flange.

The door has the usual handle 13 by which 85 it is opened and closed.

The dampers are automatically opened and closed when the door has been opened for replenishment of the fuel, by a time mechanism of the escapement type indicated 90 in its entirety by the reference character 14.

The time movement includes a gear-train 15 and an escapement in which two opposed weights 16 mounted for simultaneous adjustment at the upper end of a vertical shaft 95 17 to regulate the operation of the mechanism by their distance from the axis of oscillation of the shaft.

The time mechanism is enclosed in a dust-proof casing 18 which is fastened upon the 100 door of the furnace at a side of the rectangular flange which defines the air-opening controlled by the dampers.

An oscillating lever 19 loosely supported on the spindle 20 of the driving wheel 21 of the time movement, exteriorly of the casing, carries a pivoted pawl 22 which normally engages with a notched wheel 23 fixed

at the end of the spindle, to impart a rotary movement thereto, the arcuate movement of the lever being limited by two stops 24 and 25.

5 The time mechanism is operated by a coiled spring 26 disposed between a shoulder 27 on the lever and a thereto opposed shoulder 28 of a bell crank 29 mounted in bearings 30 on the door below the flange, 10 and a rod 31 fastened to the lever and moving freely through an opening in the shoulder of the bell crank, extends through the spring to prevent its lateral deflection.

A pin 32 on the arm of the bell crank 15 opposite that engaged by the spring, passes freely through an opening of the door to engage the frame of the boiler around the fire opening when the door is in the closed position.

20 When the fire door of the furnace is opened for the purpose of supplying the fire in the combustion chamber of the same, with fresh fuel, the pin on the bell crank is projected through the opening of the door 25 by gravity of the parts with which it is associated and the lever 19 is by the same influence moved to the position shown in Figure 2, it being understood that the opening in the door is sufficiently wide to permit 30 of the slight lateral displacement of the pin caused by the arcuate movement of the end of the bell crank arm with which it is connected.

When after the fire has been coaled, the 35 pin by contact with the furnace wall, compels the bell crank to move about its axis, the spring is compressed against the shoulder of the lever 19 held through the medium of the pawl 22 by the frictional resistance of the time-mechanism of which it is a part.

The subsequent expansive movement of the 40 spring operates the time mechanism at a rate regulated by the escapement, until the lever engages the stop 25 when the operation is automatically discontinued.

When the spring is compressed as stated hereinabove, the bell crank occupies a position in which its upper arm extends at so 50 small an angle to a perpendicular passing through the axis of its shaft, that the force resulting from the expansion of the spring will be mostly exerted upon the lever 19 of the time mechanism, while its tendency to 55 open the fire door by downward movement of the bell crank is negligible.

The time mechanism, thus actuated by the 60 spring, effects the movement of a shaft 33 which is mounted to rotate in openings of the upright portions of the door-flange and which at the side of the flange opposite to the time-mechanism, carries a cam-element 65 34 by which the dampers of the door are opened and closed.

65 The cam-element in its simplest form con-

sists of a disk having a peripheral, preferably grooved, edge of irregular form.

The edge of the cam is engaged by an anti-friction wheel 35 on the elongated wrist rod 36 of a crank 37 at the adjacent end 70 of the shaft of the upper damper, and a bar 38 connecting said rod with the wrist of a correspondingly positioned crank 39 on the shaft of the lower damper provides for the conjoint movement of the dampers. 75

It is preferred to compose the cam element of a number of steps of corresponding outlines but progressively decreasing diameters as best shown in Figure 8, to permit of varying the extent to which the dampers are 80 opened in the operation of the time-mechanism, and the wheel 35 is slidable on the wrist rod 36 for its adjustment from one step of the cam-element to another across the entire width thereof. 85

When the fire door is closed, the time mechanism is in a condition of inactivity, and the dampers close the opening defined by the flange of the door as shown in Figures 1 and 3. The wheel 35 on the crank of the 90 upper damper engages at the periphery of the step of the cam element corresponding with the extent to which the dampers are to be opened and the pawl 22 on the lever 19 is in engagement with the notched wheel 95 23 on the shaft of the driving wheel of the time-mechanism.

When in replenishing the fire in the furnace, the fire door is opened and closed, the 100 consequent actuation of the time mechanism as hereinbefore described, causes the shaft 33 to rotate with the result that through the medium of the cam-element the dampers of the door are gradually opened at a rate determined by the peripheral shape of the cam 105 with which the wheel of the crank movement is in contact.

Thus, when the cam rotates in the direction of the arrow, the dampers are opened by upward movement of the wheel 35 until 110 the latter has reached the highest point of its movement by engagement with the cam at its point of greatest diameter, after which the wheel is lowered under the influence of its own weight and that of the other members of the cam-movement of which it is a part, until the dampers are again in the closed position. 115

It will thus be apparent that the time period during which the dampers are open to 120 admit oxygen to the fire chamber, is regulated by the rate of motion of the time-mechanism under control of its escapement-governor and that the extent to which the dampers are opened and the proportionate lengths 125 of their opening and closing movements are predetermined by the shape and size of the cam.

By adjusting the contact wheel from one 130 step of the cam to another or by interchang-

ing the cam with another of different shape, the extent to which the dampers are opened and the proportionate lengths of the gradual opening and closing movements of the 5 dampers may be varied to any desired degree.

In order to preheat the air entering the furnace past the gradually opening dampers and to diffuse the same so as to spread evenly 10 over the area of the fuel bed, the door may be provided with a series of baffle plates as shown at 40 in Figure 3.

The admission of air to the fire chamber is by the adjustments hereinbefore described 15 readily regulated to correspond to the requirements of the fuel supplied to the fire and a substantially perfect combustion of the gases emanating from the burning fuel, resulting in the saving of all heat units, 20 and the elimination of smoke may thus be effected.

When it is desired to close the fire door without actuating the dampers, the pawl 22 is disengaged from the notched wheel 23 25 as shown in broken lines in Figure 2.

Having thus described my invention, what I claim and desire to secure by Letters Patent is:

1. Oxidizing apparatus for furnaces comprising in combination with the combustion chamber and fire door of a furnace, a damper controlling the admission of air to the combustion chamber, and means actuated by movement of said fire door to gradually 30 open the damper to a predetermined extent after the fire door has been closed and reclose the same.

2. Oxidizing apparatus for furnaces comprising in combination with the combustion 35 chamber and fire door of a furnace, a damper controlling the admission of air to the com-

bustion chamber, and means actuated by movement of said fire door to gradually open the damper at a predetermined rate after the fire door has been closed and re- 45 close the same.

3. Oxidizing apparatus for furnaces comprising in combination with the combustion chamber and fire door of a furnace, a damper controlling the admission of air to the 50 combustion chamber, and means actuated by movement of said fire door to gradually open the damper after the fire door has been closed and reclose the same at a predetermined rate. 55

4. Oxidizing apparatus for furnaces comprising in combination with the combustion chamber and fire door of a furnace, a damper controlling the admission of air to the combustion chamber, and means actuated by 60 movement of said fire door to gradually open the damper at a predetermined rate and to a predetermined extent after the fire door has been closed and reclose the same.

5. Oxidizing apparatus for furnaces comprising in combination with the combustion chamber of a furnace, a movable element, a damper controlling admission of air to the combustion chamber, a rotary cam, means to open the damper by movement of the 65 cam, and mechanism for operation of the cam, actuated by movement of said element.

6. In a furnace having a fire door and a damper controlling the admission of air to the furnace, means actuated by movement of the 70 fire door to open the damper after the fire door has been closed and then close the damper. 75

In testimony whereof I have affixed my signature:

ARTHUR O. HIGINBOTHAM.
